[57] CLAIM

The ornamental design for a tree support, as shown.

DESCRIPTION

FIG. 1 is a top perspective view of a tree support showing our new design, the broken line illustration of the tree trunk and stake being for illustrative purposes only and forming no part of the claimed design;

FIG. 2 is a top plan view thereof, the tubular member being shown broken-away for ease of illustration;

FIG. 3 is a right end elevational view thereof;

FIG. 4 is a left end elevational view thereof;

FIG. 5 is a rear elevational view thereof; and

FIG. 6 is a front elevational view thereof.

FIG. 3
